Atty.

UNITED STATES PATENT OFFICE.

JOHN G. BOWLES, OF CHICAGO, ILLINOIS.

AXLE LOCK-NUT.

No. 824,776.

Specification of Letters Patent.

Patented July 3, 1906.

Application filed September 15, 1905. Serial No. 278,570.

To all whom it may concern:

Be it known that I, JOHN G. BOWLES, a citizen of the United States, residing at Chicago, in the county of Cook and State of Illinois, have invented certain new and useful Improvements in Axle Lock-Nuts, of which the following is a specification.

My invention relates to that class of axle lock-nuts having shoulder portions adapted to be engaged by a locking member movable into raised central position between the shoulders of the nut and to lowered locking position in engagement with the shouldered portions of the nut, such locking member being held in non-rotatable vertically-movable position by means of a headed bolt or screw secured to the axle or thimble.

The principal object of my invention is to provide a simple, economical, and efficient axle lock-nut.

A further object of the invention is to provide axle-lock-nut mechanism having a non-rotatable locking member secured to the axle or thimble skein and movable to raised position between the shoulders of the nut and to lowered locking position in engagement with such shoulders, whereby the axle-nut may be removed without removing the locking member and the locking member moved to locking and unlocking positions while encircled by the flange of the hub.

Other and further objects of the invention will appear from an examination of the drawings and the following description and claims.

The invention consists in a shouldered axle-nut provided with a locking member mounted inside the shouldered portions of the nut and movable to locking and unlocking position, such locking member being adapted when in raised or unlocking position to permit the axle-nut to rotate around it and when in locking position to prevent such rotation.

It consists, further and finally, in the features, combinations, and details of construction hereinafter described and claimed.

In the accompanying drawings, Figure 1 is a side elevation of a skein or end portion of an axle provided with my improved axle lock-nut, showing the hub and wheel in section; Fig. 2, a central longitudinal sectional elevation of the end portion of the axle and the lock-nut mechanism, showing the locking member in locking position; Fig. 3, an end view of the headed bolt; Fig. 4, a view in elevation of the locking member; Fig. 5, an end view of the lock-nut mechanism, showing the

locking member in raised or unlocking position; and Fig. 6, a similar view showing the locking member in lowered locking position.

In constructing an axle provided with my improved axle-lock-nut mechanism I provide an axle *a*, having an end portion or skein *b*, upon which the hub *c* of the wheel is rotatably mounted in any ordinary and well-known manner, the axle and skein or thimble being of any desired and common type. The extreme outer end portions of the skein are threaded in the usual manner for receiving the axle-nut, by means of which the wheels are held in operative position. The hub of an ordinary wheel is provided with a flange *d*, which, as is well known to those skilled in the art, ordinarily encircles the axle-nut mechanism. It is therefore desirable to provide a locking axle-nut having a locking member adapted to be readily moved to locking and unlocking position while encircled by the flanged portion of the hub and adapted to prevent the possibility of the nut becoming loosened by the backward rotation of the wheel. Each of the wheels is preferably fitted with a lock-nut mechanism identical in construction, and it is therefore only deemed necessary to describe one of such lock-nut mechanisms in order to enable those skilled in the art to understand and practice the invention.

A threaded nut *e* is provided for each thimble or skein and mounted in threaded engagement therewith, as shown in Fig. 2, such nut having an annular flange *f*, adapted to hold the hub of the wheel in position upon the skein or thimble. The peripheral portion of the nut is made angular or square in the ordinary manner, so as to enable the nut to be readily turned by means of a wrench, and the squared or octagonal portion of the nut is provided with shoulders *g*, which project outward beyond the face of the nut outside of its threaded axial perforation and form spaces *h* therebetween. A bolt or screw *i*, having a head *j*, is mounted in threaded engagement with the skein or thimble at the axial center thereof, with its headed end extending outward beyond the end of the thimble. The neck of the bolt just inside the head is provided with a squared or angular portion *k*, the lower side *l* of which extends downward below the line of the cylindrical body portion of the bolt and the upper edge *m* of which is in line with the upper edge of the cylindrical body portion of the bolt. In other words,

this squared neck portion of the bolt is eccentric, and its sides are substantially parallel and vertical.

A locking member *n* is provided, having a substantially annular main body portion in the form of a disk or washer and having a squared axial opening *o*, through which the squared neck portion of the bolt extends. The lower part of this disk-like locking member is provided with a depending locking-lug portion *p* of a width corresponding to the width of the spaces *h* between the projecting shoulders *g* of the nut, such lug being of less length than the diameter of the axial opening in the locking member. When the locking member is in raised unlocking position, as shown in Fig. 5, the nut may encircle and rotate entirely around it. When the locking member is in lowered or locking position, as shown in Figs. 1, 2, and 6, the locking-lug portion extends between the lowermost shoulders of the nut and holds it securely against rotation.

To permit the movement of the locking member to raised unlocking and lowered locking position, its axial opening is of such length from top to bottom as to permit its vertical movement in sliding engagement with the squared neck portion of the bolt *i*, and such neck portion is eccentric not only with relation to the main body portion of the bolt, but also with relation to the nut and skein, being below its axial center. By this means it will be readily seen that the upper edge of the squared neck portion of the bolt permits the locking member to be lowered to locking position and that the lower edge of such squared neck portion engages the locking member when in raised position and prevents it from being raised so as to interfere with the rotation of the nut when being removed. The rotation of the nut around such locking member is thus permitted when the locking member is in raised unlocked position.

In order to provide additional security against the accidental loosening of the locking member, its depending lug is provided with a lip portion *q*, which projects slightly beyond its inner surface, so as to engage the nut sufficiently to prevent the locking member from being accidentally moved to unlocking position. The lip is sufficiently short and inclined to permit the locking member to be raised to unlocking position by means of upward pressure when desired.

The locking member constructed as above described, with the vertical side walls of its axial perforation in sliding engagement with the eccentric neck portion of the bolt, efficiently holds the nut against rotation. When in raised unlocking position, it enables the axle-nut to be readily removed and replaced while encircled by the flange of the hub. The possibility of the axle-nuts being unscrewed

by the backward rotation of the vehicle-wheels is thus entirely obviated and the danger of accidental removal of the wheels removed.

I claim—

1. In mechanisms of the class described, the combination of a shouldered nut provided with an axial perforation, a locking member having a portion movable into locking engagement with the shoulders of the nut and into unlocking position between the shoulders and the axial center of the shouldered portion of the nut, and means for supporting such locking member in locking and unlocking positions.

2. In mechanisms of the class described, the combination of a shouldered threaded nut, a locking member movable transversely of the nut into engagement with the shouldered portion of the nut and adapted to permit such nut to encircle and pass thereover when the locking member is in unlocking position, means for movably supporting such locking member, and a skein member provided with a threaded portion on and in threaded engagement with which such nut is mounted.

3. In mechanisms of the class described, the combination of a shouldered nut, a locking member movable into engagement with the shoulder portions of the nut and adapted to permit such nut to encircle and pass thereover when the locking member is in unlocking position, and a supporting-bolt extending through the axial center of the nut and through the locking member for supporting such locking member non-rotatably and in vertically-movable position.

4. In mechanisms of the class described, the combination of a shouldered nut having an axial perforation, a locking member provided with a perforation having substantially parallel side wall portions, a supporting member provided with side portions in sliding engagement with the side walls of the perforation in the locking member and adapted to permit the vertical movement of such locking member thereon.

5. In mechanisms of the class described, the combination of a shouldered nut, a headed bolt extending through such nut and provided with a neck portion having substantially vertical sides, and a locking member provided with a perforation having substantially parallel side walls in sliding engagement with the neck portion of the bolt movable to unlocking position and to lowered position in locking engagement with the shouldered portion of the nut, such locking member being supported in both locking and unlocking positions by the bolt.

6. In mechanisms of the class described, the combination of a shouldered nut, a headed bolt extending through the nut and provided with a neck portion having substan-

tially vertical sides, and a locking member provided with a perforation having substantially vertical side walls in sliding engagement with the neck portion of the bolt and having a portion movable to raised unlocking position between the shoulders and the axial center of the shouldered portion of the nut and to lowered position in locking engagement with the shouldered portion of the nut.

7. In mechanisms of the class described, the combination of a shouldered nut, a headed bolt extending through such nut and provided with an eccentric neck portion having substantially vertical sides, a locking member provided with a perforation having substantially vertical side walls in sliding engagement with the eccentric neck portion of the bolt and having a portion movable to raised unlocking position between the shoulders and the axial center of the shouldered portion of the nut and to lowered position in locking engagement with such shouldered

portion of the nut, and an axle member provided with a threaded portion upon which such nut is mounted.

8. In mechanisms of the class described, the combination of a shouldered threaded nut, a headed bolt extending through the nut and provided with a squared neck portion, a locking member provided with a perforation having substantially parallel vertical side walls in sliding engagement with the squared neck portion of the bolt movable to raised unlocking position and to lowered position in locking engagement with the shouldered portion of the nut, and a skein provided with a threaded end portion in threaded engagement with such nut and having a central axial perforation in which such bolt is mounted.
